UNITED STATES PATENT OFFICE.

ARCHIBALD F. WRIGHT AND WALTER A. STONE, OF ST. CLAIR, MICHIGAN.

RUBBING BLOCK.

Application filed October 31, 1921. Serial No. 511,671.

To all whom it may concern:

Be it known that we, ARCHIBALD F. WRIGHT and WALTER A. STONE, both citizens of the United States of America, residing at 5 St. Clair, in the county of St. Clair and State of Michigan, have invented certain new and useful Improvements in Rubbing Blocks, of which the following is a specification, reference being had therein to the 10 accompanying drawings.

The invention relates to rubbing blocks particularly designed for use in the finishing or smoothing of wood-work by sand paper or other abrasive material. It is the 15 object of the invention to obtain a construction which may be used with various structures and which is provided with means for finishing of angles, grooves and other surfaces which are not in a single plane. It 20 is a further object to provide a convenient means for clamping to the block the sand-paper or other abrasive material, and with these objects in view the invention consists in the construction as hereinafter set forth.

25 In the drawings:

Figure 1 is a perspective view of the block;

Figure 2 is a cross-section thereof;

Figure 3 is a longitudinal section.

30 Figure 4 is a perspective view showing a modified construction of clamping plate.

A is the block, preferably of rectangular form, and having its lower face B in a plane. One of the edges of this block has the convex rounded surface C, while the opposite edge is formed with a concave rounded surface D. The narrow edge portion E between this concave surface and the plane B projects outward beyond the edge F at 40 the top of the block, as indicated in Figure 2. A third edge of the block is formed with the angle section G, while the opposite edge is formed with the angle groove H. I is a clamping plate, preferably formed of 45 pressed sheet metal, having the downturned marginal flanges J. This plate is secured by a screw or other fastening K, which projects through a slot in the plate and engages a wedge L. This wedge is preferably located in an inclined depression M formed in the plate I.

With the parts formed as described, in use, a piece of sand-paper, or other sheet of abrasive material, is drawn about the bottom of the block and over the edges thereof so as to extend obliquely inward at the top.

The plate I is then placed over the edge portions of the sheet and the wedge L is moved to effect the clamping of this plate upon the block. When the abrasive material is thus 60 secured, the block may be used either for rubbing a plane surface or for finishing any moldings and other angling and curved surfaces. The projection of the edge portion E beyond the edge portion F permits of using 65 the block immediately adjacent a perpendicular surface without interference with or marring of the latter. The outwardly projecting angling portion G is useful in finishing angle grooves, while the 70 angle groove H is useful for finishing corners. These portions are preferably formed with one side of the angle of greater width than the other, as indicated at G' and G'' of Figure 3. We have found this to be of 75 convenience in obtaining easy access to certain portions of the work.

The abrasive sheet may be adjusted or exchanged as frequently as desired by merely disengaging the wedge L and removing the 80 clamp I. When not in use, the block may be conveniently hung up by providing an aperture N in the plate I with a narrow slot O leading from one side thereof. The 85 large aperture N permits insertion of the head of a nail or screw while the slot O engages the shank and prevents slipping off. Thus the device is one which is exceedingly useful and convenient.

While we have described my improvement 90 as used for the polishing of wood, it is evident that it is equally applicable for polishing metals, rubbing varnished surfaces and for other uses. Also, in place of sand paper or emery cloth, cotton, wool or other 95 fabrics may be used upon the block and secured by the clamp.

Figure 4 shows a modified construction of clamping plate where, in place of the straight wedge, we employ a circular wedge 100 L' which is pivotally secured to the plate I by a rivet P and which has the slot Q for the passage of the headed screw K. There is also a lug R projecting from the plate for the turning of the same. Thus the rotation 105 of this wedge will force the thickened portion thereof between the head of the screw and the plate, exerting a clamping pressure on the latter.

What we claim as our invention is:

1. A rubbing block comprising a body portion having a plane rubbing surface and

edge portions varying in contour, a clamping plate for engaging the surface of said body opposite said plane rubbing face, said clamping plate being formed of pressed sheet metal having depending marginal flanges and a depressed central portion, a clamping wedge for engaging said depressed central portion, and a cooperating headed fastener secured to said body.

10 2. A rubbing block having a plane rubbing face and edge portions of varying contour, said block also having a top face parallel to said plane rubbing face, abrasive material adapted to engage the parallel faces

and edge portions of said block, a clamping member for engaging said abrasive material, a wedge engaging said clamping member for applying the clamping pressure thereto, and means for securing said clamping member to the top face of said block and for retaining said wedge in adjusted position to clamp said abrasive material upon said block.

In testimony whereof we affix our signatures.

ARCHIBALD F. WRIGHT.
WALTER A. STONE.
